COMBINED VASE AND FLOWER HOLDER

Signe H. Persson-Melin, Sanekullavagen 16,
217 74 Malmo, Sweden

Filed Apr. 14, 1972, Ser. No. 244,333

Claims priority, application Sweden Oct. 14, 1971

Term of patent 14 years

Int. Cl. D11—02

U.S. Cl. D29—28 R

FIG. 2

FIG. 1

FIG. 1 is a perspective view of a combined vase and disk flower holder showing my new design; and

FIG. 2 is a plan view of the disk flower holder removed from the vase.

I claim:

The ornamental design for a combined vase and flower holder, substantially as shown.
